(57) **CLAIM**

The ornamental design for a beverage tray with wireless charger, as shown and described.

DESCRIPTION

FIG. 1 is a front perspective view of the beverage tray with wireless charger showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and

FIG. 7 is a bottom plan view thereof.

FIG. 8 is a front perspective view thereof showing the beverage tray with wireless charger in an environment of use; and,

FIG. 9 is a front perspective view thereof showing the beverage tray with wireless charger stacked on a charging station and being charged.

The dot-dash broken lines depict the boundary of the claim and form no part of the claimed design. The dashed broken lines throughout the drawing figures depict environmental subject matter that forms no part of the claimed design.

1 Claim, 6 Drawing Sheets
